CLAIM

The ornamental design for a shoe midsole periphery, as shown and described.

DESCRIPTION

FIG. 1 is a perspective view of a shoe midsole periphery in accordance with my new design; and,

FIG. 2 is a left side elevation view thereof.

The broken lines shown in the drawings represent portions of the shoe midsole periphery that form no part of the claimed design.

The surfaces devoid of shading lines are not claimed.

1 Claim, 2 Drawing Sheets See application file for complete search history.
